UNITED STATES PATENT OFFICE.

THOMAS W. SMITH, OF LONDON, ENGLAND.

DESIGN FOR A FONT OF TYPE.

SPECIFICATION forming part of Design No. 16,032, dated April 7, 1885.

Application filed February 18, 1885. Term of patent 7 years.

To all whom it may concern:

Be it known that I, THOMAS W. SMITH, of London, England, have invented and produced a new and original Design for a Font of Type, 5 of which the following is a full, clear, and exact description.

Reference is to be had to the accompanying typographic impression, which fully illustrates my design.

10 The leading feature of my design consists in the light scrolls terminating in a central dot placed in the spaces of both the upper-case letters and the lower-case letters, and at the sides of the upright lines of such letters 15 as F I J L P T Y. The letters of the upper case, except C G O Q S, have in their middle parts short cross-lines with one or both ends

tapered to a point and curved. The lower-case letters, except a e g s z, have a light curved line connected with their scrolls. 20 Such of the letters in both cases as have straight lines in their formation are widened toward the ends and have laterally-projecting points at their said ends. The curved lines of such letters as B D P R S have laterally-projecting points. 25

I claim—

The design for a font of type herein shown and described.

THOMAS W. SMITH.
